FIG. 2

Des. 194,665

FIG. 4

FIG. 1 is a perspective view of an automobile tonneau cover, showing my new design in use. The portion of an automobile shown in broken lines is for the purpose of illustration only;

FIG. 2 is a front elevational view of the tonneau cover; FIG. 3 is a plan view thereof; and

FIG. 4 is a side elevational view thereof.

I claim:

The ornamental design for an automobile tonneau cover, substantially as shown and described.
